Thomas Howe ATTORNEY

UNITED STATES PATENT OFFICE.

FRIEDERICH MÜLLER, OF ELIZABETH, NEW JERSEY.

JOINT FOR GOLF CLUBS.

Application filed June 21, 1927. Serial No. 200,318.

This invention relates to golf clubs and more particularly to the method of joining the head of the club onto the shaft.

It has for its object the provision of means for rigidly securing the head of a golf club onto the shaft as well as protecting the joint between the two parts.

Another object is to arrange a ferrule upon the joint between the head and shaft of a golf club which is seamless in its construction and of uniform material throughout. Such a construction and the process for carrying it out render it particularly adaptable for use on a joint in a golf club. The sleeve thus formed conforms to the shape of the joint and touches every point. Methods heretofore used for applying such a sleeve have been more or less ineffective, inasmuch as they do not conform strictly to the shape of the joint.

Another object of this invention is to apply a sleeve to the joint between the shaft and the head of a golf club by a special process which includes electro-depositing metallic material onto the outside of the joint in such a way as to closely conform to the surfaces and interlock with any irregularities. This interlocking can be enhanced if desired, by providing screw threads or other forms of ridges, indentations or the equivalent on the adjacent surfaces of the two parts. This construction adds to the security and rigidity of the joint in a golf club and is particularly adapted to such a joint on account of the closeness of the fit obtainable. This sleeve may be formed in one piece in this manner without seams or other joints at which points of weakness may develop.

Further and more definite objects may be appreciated and particularly pointed out in connection with the following specification, claims and drawings, in which

Fig. 1 is an assembled view of a golf club embodying the invention;

Fig. 2 shows an enlarged view of the joint in which the end of the shaft and of the head is broken away, showing part in section;

Fig. 3 shows the arrangement of the adjacent surfaces of the head and shaft prior to depositing the metal thereon; and

Fig. 4 shows the club in the position which it occupies in the process of applying the sleeve.

The shaft 1 of the club may be connected

with the head 2 by the joint 3. This joint 55 may be of the form shown in Fig. 2 in which the shaft 1 is shown in the form of a tapered hollow tubular member having a tapered end portion 4 inserted within the recess 5 of the tapered socket portion or shank 6 which is formed integral with the head 2 of the golf club. If desired, a shoulder may be arranged at the end of the sleeve 8 in the socket portion 6 so that the outside surface of the sleeve will be even with the surface of the socket. However, this construction is not necessary to the successful carrying out of the invention.

The shaft 1 may be inserted within the recess 5 when an arrangement as shown in Fig. 3 may be provided. If desired, a series of screw threads or other form of ridges or grooves 9 and 10 may be formed in the shaft or head portions or both. When the two parts have been combined, the wooden or other nonconducting surfaces may be covered to the desired extent with graphite or other electrically conductive medium 12 which may be caused to adhere in any suitable and well known manner. A rubber tube 11 as shown in Fig. 4 or other insulating coating may be applied to the part to be immersed in the chemical solution and which it is intended to remain unaffected by the solution. This tubing should be closely fitted so that no liquid can come in contact with the parts covered thereby and is removed after the process has been completed. Contact is made with the graphite or other conducting surface 12 by any proper means such as the wire 13, and another electrical connection may be made to the solution or bath 14 by means of plate 15 properly connected to a source of potential (not shown).

A salt of the metal to be coated on the joint is dissolved in the solution 14 and upon the passage of current between the plate 15 and the wire 13 in the proper direction as is well understood in the art of electro-deposition, a metallic coating will be electro-deposited on the coating 12 and upon the adjacent surface of the metal shaft which is in electrical connection with the coating 12. The manner of depositing the metal on the joint is according to the well-known practices and materials employed in electro-deposition. Thus if a deposit of copper is desired, the usual methods and materials,

and materials for depositing copper would be employed, and so with other metals, the usual methods and materials employed in their deposition respectively being employed. 5 Such a deposit is shown at 8 in Fig. 2 in the form of a sleeve of substantial thickness which covers the joint thereby protecting it from moisture, dust, etc., as well as strengthening it and adding to the rigidity. Also, 10 the sleeve might be formed of other materials, as for instance, of rubber, electro-deposited as described in an article entitled "Molding rubber with electricity, a new electrolytic process" appearing on page 677 15 of the June 1927 issue of the publication entitled Mechanical Engineering.

The sleeve also aids in preventing the separation of the two parts on account of the grooves 9 and 10 into which the metal has 20 been deposited, conforming to the shape of the joint and adjacent surfaces, and touching at every point.

It can thus be seen that a sleeve is applied to a joint between two reversely tapered surfaces, which is homogeneous throughout its 25 extent and without seams or other inherent lines of weakness. The sleeve may be applied to any type of golf club utilizing metallic or wooden heads or shafts. In the 30 particular structure shown, a metallic shaft is described in connection with a wooden head but it is not intended to be limited to this construction inasmuch as both shaft and head may be of metal, both may be of wood or other suitable electrically insulating 35 material, or one may be of metal and the other of wood. Where metal is used no coating 40 is needed on the metal part, the electro-deposition being restricted to the desired part by permitting that part only to come into contact with the bath 14. In the case of a wooden or other non-conducting member, the deposition is produced on the area 45 desired by applying the graphite or other conducting covering to that area.

While the invention has been illustrated in what are considered its best applications, the invention may have its product embodied in structures other than that shown in the 50 drawings and the process may have its details varied, without departing from the spirit of the invention; the invention is not, therefore, limited to the structure shown in the drawings nor to the precise details of the 55 method as recited.

What I claim is:

1. In a golf club, the combination with a head having a tapering shank portion into 60 which is inserted a handle having a taper in a reverse direction, means for securing said head and handle in inseparable relation comprising a sleeve of electro-deposited material.

2. In a golf club, a head portion, a shaft portion and an element for securing said

portions together comprising a sleeve electro- 65 deposited thereon.

3. In a golf club, the combination with a head having a grooved tapering shank portion into which is inserted a handle having a taper in a reverse direction, means for securing said head and grooved handle in inseparable relation comprising a sleeve of electro-deposited material about said grooved portions. 70

4. In a golf club, the combination with a head and shaft, having reverse tapers and one being inserted within the other, and a seamless reinforcing sleeve electro-deposited about said head and shaft adjacent the point of insertion. 75

5. A golf club having a head and a shaft joined thereto by an electro-deposited sleeve.

6. In a golf club, the combination with a wooden head having a tapering externally grooved shank, a grooved handle having a 85 taper in reverse direction which is inserted into an opening in said shank, and an electro-deposited sleeve for securing said head and handle together through interlocking with said grooves. 90

7. A golf club having two members including a head and a shaft and indentations in one of said members adjacent their joint, and a sleeve electro-deposited thereon.

8. A golf club having a head, a socket 95 therein, a metallic shaft inserted in the socket, ridges and depressions formed on the outside of the socket and shaft for maintaining a rigid sleeve in position thereon.

9. A golf club having a head, including a 100 tapered shank, a shaft inserted in said shank and having a tapered portion adjacent the point of insertion, indentations in said club adjacent said point of insertion, and metallic means applied to the joint and said indentations for rigidly combining said head and shaft. 105

10. A connection between a socket having indentations on its outside surface and an inserted piece having indentations including 110 an electro-deposited reinforcing sleeve.

11. A golf club having a head connected to a shaft by means of an electro-deposited sleeve and means for providing an interlock 115 between said parts.

12. In a golf club, a head portion, a shaft portion and an element for securing said portions together comprising a sleeve formed thereon by depositing material in a finely divided state. 120

13. In a golf club, the combination with a head and shaft, having reverse tapers and one being inserted within the other, and a seamless sleeve found about said head and shaft adjacent the point of insertion by depositing material therein in a finely divided state. 125

14. A golf club having a head, a recess in

said head, a tapered shaft inserted in said recess and a sleeve, formed by deposition of material in a finely divided state, about said head and shaft adjacent the point of insertion.

15. A golf club having two members including a head and a shaft, at least one of said members having indentations adjacent their joint and a sleeve formed by depositing material in a finely divided state upon said head and shaft adjacent their joint.

16. In a golf club, a head portion of wood,

a metal shaft portion and an element for securing said portions together comprising a sleeve formed thereon by depositing material in a finely divided state.

17. In a golf club, a head portion of wood, a metal shaft portion and an element for securing said portions together comprising a metal sleeve formed thereon by depositing material in a finely divided state.

In testimony whereof I have signed this specification this 6th day of June, 1927.

FRIEDERICH MÜLLER.
